(57) **CLAIM**

The ornamental design for an aerial vehicle, as shown and described.

DESCRIPTION

1. Aerial vehicle
2. Aerial vehicle
- 1.1 : Perspective
- 1.2 : Perspective
- 1.3 : Front
- 1.4 : Back
- 1.5 : Left
- 1.6 : Right
- 1.7 : Top
- 1.8 : Bottom
- 1.9 : Enlarged
- 1.10 : Enlarged
- 1.11 : Enlarged
- 1.12 : Folded state
- 2.1 : Perspective
- 2.2 : Perspective
- 2.3 : Front
- 2.4 : Back
- 2.5 : Left
- 2.6 : Right
- 2.7 : Top
- 2.8 : Bottom
- 2.9 : Enlarged
- 2.10 : Enlarged
- 2.11 : Enlarged
- 2.12 : Folded state

1. The dash-dash broken lines in the drawings depict the portions of the aerial vehicle which form no part of the claimed design.
2. The dot-dash broken lines in FIGS. 1.1, 1.5, 1.9, 1.10, 1.11, 2.1, 2.5, 2.9, 2.10 and 2.11 are for the purpose of annotating the enlargements and form no part of the claimed design.

1 Claim, 24 Drawing Sheets
